UNITED STATES PATENT OFFICE

EDWARD R. HANGLITER, OF WASHINGTON, DISTRICT OF COLUMBIA.

INJECTOR FOR VACUUM CLEANING AND OTHER PURPOSES.

1,177,947.

Specification of Letters Patent.

Patented Apr. 4, 1916.

Application filed September 15, 1911. Serial No. 649,455.

To all whom it may concern:

Be it known that I, EDWARD R. HANGLITER, a citizen of the United States, and a resident of the city of Washington, District of Columbia, have invented certain new and useful Improvements in Injectors for Vacuum Cleaning and other Purposes; and I do hereby declare the following to be a full, clear, and exact description of the invention, such as will enable others skilled in the art to which it appertains to make and use the same.

This invention relates to vacuum cleaning and has for its object to provide an injector which, when used in combination with the usual vacuum cleaning apparatus, will co-operate therewith in a novel manner to entrain the dust and discharge it where no further handling is necessary.

My injector has the advantage that a maximum surface of rapidly moving water is brought into contact with the dust laden air, which is thereby strongly entrained and carried off with the water to a suitable place of discharge. In practice, the water supply is usually provided from the ordinary service pipes when the vacuum cleaner is installed in a house or other building, the injector casing being preferably connected with the service pipe within the cellar of the building or at any other suitable point. The dust pipe connected to the injector casing preferably extends upward through the building and is provided on each floor with a suitable detachable connection for the usual flexible suction tubes. The construction of the injector is such that when it is installed in the general relation specified, a comparatively high degree of vacuum is created in the suction pipe without the employment of an excessive water pressure, which result is primarily due to the construction and arrangement of the means for creating the water jet, the means for directing the water to the jet opening, and the relation of the jet so formed in respect to the air chamber of the injector.

In the accompanying drawing, Figure 1 is a general diagrammatic view showing the injector as applied to a vacuum cleaning system in a house or other building. Fig. 2 is a vertical central section, on an enlarged scale, of the injector shown in Fig. 1, and Fig. 3 is a view similar to Fig. 2; but illustrating a modified construction.

Referring to the drawing, and particu-

larly to Fig. 1, a section of water pipe 10 located in the cellar and connected with the service line or main, is connected with the casing 11 of an injector A, the particular construction of which will be hereinafter described. Leading off from the top of the injector casing 11 is a dust or air pipe B extending upward through the building and provided at each floor with a valved connection b by means of which it can be connected in an obvious manner with one or more flexible suction tubes b'. Each suction tube b' is equipped with one of the usual suction nozzles b''. The air sucked up through the tube or tubes b' by the action of the water passing through the injector in a manner to be hereinafter described, produces the carrying off of the dust and dirt in a downward direction through the pipe 75 B and through the injector A, whence it passes, together with the water from the service pipe, into a downwardly directed discharge pipe C leading from the bottom of the injector casing. The lower portion 80 of the discharge pipe C is provided with a trap e or other device to conserve a vacuum in the pipe B, and it is obvious that the water pipe should be provided with a suitable valve or cock (not shown), by means 85 of which the operation of the injector may be begun and arrested as desired.

Referring more particularly to Fig. 2, which shows in detail the construction of the injector illustrated in Fig. 1, it will be seen that the injector casing 11 is comparatively wide at its upper part, i. e. where it is connected with the water pipe 10, while at its lower portion, it is of narrow elongated shape and preferably curved in the manner shown. The pipes B and C may be screwed into the top and bottom respectively of the casing, as shown, and they extend vertically, while the water pipe 10 extends horizontally, i. e. at right angles to the aforesaid pipes. Water delivered to the injector casing from the pipe 10 passes into a central water chamber 12 formed by a shell 13 supported centrally within the casing by means of a spider 14 (a portion only of which is shown), and in direct communication with the water inlet of the casing by means of a short lateral branch 15. The upper end of the shell or compartment 13 is provided with an opening 16, in which is secured an air deflecting plug 17, which is preferably screwed into the opening 16 in the manner

shown. The plug 17 is preferably of conical shape and directed upwardly toward and into proximity to the inlet opening at the top of the casing, whereby the air sucked 5 downward into the injector from the pipe B is deflected laterally around the water chamber 12. The air passes downward over the outside surface of the water chamber and through the openings of the spider 14. The 10 lower end of the water chamber or shell is provided with a comparatively small opening 18 in which is centrally located a button or disk 19 formed at the lower end of a stem 20 depending from the plug 17 and 15 preferably integral therewith. The button 19 is of cylindrical shape and forms in connection with the opening 18 an annular discharge opening for the water jet, which therefore assumes a hollow cylindrical shape 20 and passes downward through the laterally restricted portion 21 of the casing, in close proximity to the walls thereof, thereby entraining the body of dusty air which has found its way into the substantially annular 25 air chamber surrounding the water chamber.

One of the most important features of the invention is the means for directing the water downward through the injector casing in the form of a substantially cylindrical jet, 30 whereby a maximum surface of dust entraining water is presented to the dust laden air descending in the air chamber. The jet formed by the annular opening defined between the button 19 and the bottom opening 35 in the water chamber, passes in close proximity to the walls of the reduced lower portion of the injector casing, so that thereby the body of dust laden air in the outer part of the casing is sucked inwardly and downwardly, *i. e.* into the descending centrally located water jet. In this manner, a high 40 vacuum is maintained in the suction pipe B when the apparatus is in operation, and as a consequence a maximum amount of dust 45 is sucked into the water jet and carried off through the discharge pipe C, which preferably empties into the sewer, so that the dirty water is directly and satisfactorily disposed of. The trap *c* or similar device located in the discharge pipe prevents air 50 from rising in the latter and thereby decreasing to any extent whatever the vacuum in the suction pipe. As the water inlet pipe and the discharge pipe are at substantially right angles to each other, the inflowing water has to turn at right angles within 55 the injector casing. Under ordinary conditions, this would produce a whirling or disturbance of the water in the water chamber 60 such as would prejudice the formation of a homogeneous and uniform jet; but I overcome this disadvantage by placing a deflecting vane or baffle 22 in the water chamber, preferably at the side opposite the inlet 65 branch 15. The vane 22 may be conven-

iently mounted on the plug stem 20, with which it is preferably made integral, and it should extend practically throughout the height of the water chamber, so as to prevent any rotary or swirling movement in 70 the latter. In this manner, the incoming water is divided into two portions and prevented from forming a swirl above the jet, where the formation of the latter in a uniform manner would be prejudiced.

I have found that in a device of this kind the air chamber surrounding the water chamber is apt to become clogged to a certain extent with dirt of various kinds sucked 75 through the suction pipe. It is therefore 80 desirable to provide some means for cleaning out the air chamber periodically, as such becomes necessary, and in order to effect this result I have devised the following arrangement wherein the cleaning of the air chamber may be easily effected by means of a stream of water derived directly from the water supply pipe. Although there are many different ways of carrying out this 85 idea, I have illustrated, by way of example, 90 a by-pass 30 formed in the casing of the injector and leading from the water chamber to the upper portion of the air chamber, said by-pass being normally closed by a cock 31 having a through opening or bore 32, the 95 ends of which are adapted to be brought into register with the respective branches of the by-pass, between which branches the cock is interposed. The cock may be readily operated by means of a small hand lever 33, and when it is moved into the position shown in Fig. 2, a portion of the water entering through the pipe 10 will pass upward 100 through the by-pass 30 and thence flow downwardly in a strong current through 105 and around the air chamber. In this manner, said chamber may be thoroughly cleared 110 of impurities which are carried off in the water current through the discharge pipe.

Fig. 3 illustrates a modified construction 110 in which the water pipe and the suction pipe have a relation opposite to that previously described, that is to say, the water pipe 10^a enters the injector casing at the top 115 while the suction pipe B' enters the casing from the side. In this instance, the necessity for a deflecting vane in the casing is dispensed with, and the water flows downward directly from the inlet pipe into a central water chamber 12^a which may be 120 conveniently formed by an open-topped shell 13^a screwed into the top of the casing and receiving, in turn, the lower end of the water pipe 10^a. The water jet is created at 125 the bottom of the water chamber in the same manner hereinbefore described, but the button 19^a must necessarily be differently mounted. In the embodiment illustrated, 130 said button is carried by a stem 20^a screwed into a spider 23 at the intermediate portion

of the water chamber. With this construction; the air sucked into the casing through the suction pipe B' can pass freely around the shell 13^a without any obstruction whatever, and it is sucked downward around the lower portion of the water chamber and into the substantially cylindrical water jet.

In the modification just described the flushing out of the air chamber may be effected by means of a by-pass 30 and cock 31 similar to those previously described. In this case, however, the flushing water takes an opposite course, that is, it moves downward from the top of the water chamber into the upper portion of the air chamber. The water issuing from the discharge end of the by-pass is deflected entirely around the air chamber by means of a baffle 34, so that the air chamber is flushed out thoroughly over its entire cross sectional area.

Of course it will be understood that I have not attempted to describe all of the various modifications of the device which may be adopted without departing from the spirit of my invention.

What I claim is:—

1. An injector such as described, comprising a casing divided into separate chambers, and a by-pass connecting said chambers, whereby one of the same may be flushed out by a portion of the fluid from the other during operation of the injector.

2. An injector such as described, comprising a casing divided into a water chamber and an air or dust chamber, and a regulable by-pass placing said chambers in communication, whereby one of the same may be

flushed out by a portion of the fluid from the other during operation of the injector.

3. An injector such as described, comprising a casing, a shell therein defining a water chamber having a jet outlet, the space around the shell constituting an air chamber, a by-pass leading from the water chamber to the air chamber whereby the air chamber can be flushed out by a portion of the water from the water chamber during operation of the injector, and a cock in said by-pass.

4. A vacuum cleaning apparatus comprising a current-inducing device which consists of a chamber having a jet inlet with a water nozzle therein, an air inlet pipe, an outlet pipe for both air and water and in line with the jet inlet, a water inlet passage, and a flushing channel encircling the upper portion of the chamber and connected with the last mentioned passage.

5. A current-inducing apparatus for vacuum cleaners consisting of a head having a jet inlet for water and an air inlet pipe, a flushing channel at the bottom of the head, a water inlet connected to the channel, a chamber secured to the bottom of the head and having an outlet opening in line with the jet inlet, and an outlet pipe connected to the outlet of the chamber.

In testimony whereof I affix my signature, in presence of two witnesses.

EDWARD R. HANGLITER.
